10 Claims. (Cl. 146—130)

1

The present invention relates to a meat-skinning machine, which is characterised in that it comprises a feed shaft rotatably and drivably mounted in a frame, and a blade displaceably guided in the frame and having a cutting edge extending along the feed shaft, the feed shaft having on its surface projections adapted to carry along the skin and having formed therein a helical groove in which a helical spring is mounted with such radial clearance that, when pressed fully into the groove in the region of a cutter under the radial bearing pressure of the skin, it projects beyond projections to enable them to engage the skin, and, conversely, it projects beyond the projections in the region further from the blade to an extent sufficient to detach the skin from the said projections. Thus, by means of the arrangement and dimensioning of the spiral spring, the projections can in general be made to project only at the points at which this is necessary to enable them to engage the skin so that a forward feed of the skin and of the meat to be skinned in the necessary working region is ensured. As soon as the skin leaves this region, it is correspondingly radially shifted by the spiral spring leaving the groove, so that it is automatically detached from the projections without any special stripping means being required. However, in addition to these functions serving to provide a direct operating process, the spiral spring also affords a very desirable protection of the fingers of the operator guiding the meat past that point of the feed shaft which lies in the region of the blade and whose fingers might therefore come into contact at this point with the shaft and with the projections if the spiral spring did not also shield the projections at these points.

An embodiment of the invention is illustrated by way of example in the accompanying drawings in which:

Figure 1 is a cross-section on the line A—A of Figure 2;

Figure 2 is a plan view;

Fig. 3 shows in small scale a side elevation of the entire device;

Fig. 4 is a front view thereof;

Fig. 5 shows in large scale a section along lines B—B of Fig. 4; and

Fig. 6 shows in similar large scale a section along lines C—C of Fig. 3.

The meat-skinning machine provided by the invention comprises a feed shaft 1 supported at its ends in bearings 2 and 3. The two bearings 2 and 3 are connected together by a frame 4 in

5 the form of a longitudinal web. The portion of the frame forming the bearing 2 is constructed as a coupling head intended for connection to meat-cutting machines of the usual kind and is accordingly provided with the three conventional radial lugs 5 one of which has a longitudinal slot 6. The shaft 1 has, at the same end, a corresponding recess 7 adapted to receive the driving pin on the shaft of a conventional meat-cutting machine. Thus, by connecting the coupling head to a meat-cutting machine and inserting the driving pin in the recess 7, the skinning machine can be fitted for use in the driving position of a meat-cutting machine, the shaft being driven in the direction of the arrow 8 as soon as the motor of the meat-cutting machine is started.

10 The driving shaft 1 has projections 9 formed by a number of longitudinal ribs arranged at regular intervals over the entire peripheral surface of the shaft and subdivided by a helical groove 10 extending the entire length of the shaft. A helical spring 11 is mounted in the groove 10 with a radial clearance with respect to the base thereof. The clearance and the dimensions of the spring are such that the spring takes up such a position when fully pressed into the groove at any desired position that the driving projections 9 project beyond the convolutions of the spring 11 at the said position but, at the 15 diametrically opposite position, the convolutions of the spring 11 project to such an extent that the projections 9 are completely screened; there is a gradual transition in the intermediate zones. The longitudinal frame 4 is provided with two 20 perpendicular bearing sockets 12 and a pin 13 is vertically displaceable in each socket 12. These pins 13 are mounted on a common knife blade 14 which has a cutting edge 15 extending along the shaft 1. The sockets 12 therefore act as 25 guides for the upward and downward movement of the blade 14.

25 As will be seen from Figure 1, the blade is provided, on the side facing the shaft, with a blunt edge 16 behind, and parallel to, the cutting edge 15, the blunt edge serving to prevent the cutting edge from cutting into the skin and to exert a scraping action. Adjoining the edge 16, the 30 blade has a hollowed portion 17, the radius of curvature 18 of which exceeds the radius of the shaft 1. By reason of this, and due to the position of the hollowed portion 17, damage to the cutting edge 15 and to the edge 16 by the rotating 35 projections 9 when the blade is fully lowered on to the shaft 1 is prevented, because the hollowed portion 17 first encounters the projections 9 so

2

that the cutting edge 15 and the edge 16 cannot come within reach of the projections 9.

According to Figs. 3 and 4, the coupling head is inserted into a machine support 19, which is provided, in a manner not shown, with an electric motor, by means of which the shaft 1 together with helical spring 11 may be continuously rotated. On the blade 14 between both pins 13 there is provided a pin 20 in the form of a toothed rack, which extends in a socket 21 of the frame 4, the teeth 22 of which are in engagement with the gear segment 23 of a pinion 24. The pinion 24 is rotatably mounted in a bearing in longitudinal frame 4 and has at one end a central pin 25, which is inserted through an aperture in frame 4 and terminates in a threaded pin on which a nut 26 is arranged. By this means the pinion 24 is secured against axial displacement. The other end of pinion 24 is provided with a hub 27, which protrudes from frame 4 and carries a one-arm lever 28. At the free end of this lever 28 a connecting rod 29 is connected, the rod 29 also being connected to the frame 4 by a spring 30 which is attached to the middle of the rod. The lower end of the connecting rod 29 is linked to a pedal 31, which is rotatably mounted on a horizontal axle at the foot 32 of support 19.

As is evident, the spring 30 urges connecting rod 29 upwardly and thereby tilts rocking lever 28 to its highest position. Therefore blade 14 by virtue of pinion 23, 24 and rack 20, 22 is placed in its furthest position from shaft 1. If the operator now depresses pedal 31, he can place edge 16 of the blade closer to shaft 1, and if he releases the pedal, he can move the edge 16 away from the shaft.

In operation, the motor driving the rotating shaft 1 is started and the meat is fed by the operator from the right-hand side of Figure 1, the skin lying nearer the shaft, that is to say, lowermost. The cutting edge 15 is brought to the required distance for separating the skin by operation of the pedal. The spring 11 is urged completely into the helical groove 10 by light pressure on the meat, so that the driving projections, which then project beyond the spring, engage the meat and carry it forward against the cutting edge 15. The cutting edge 15 then removes the skin, which is bent inwardly to such an extent by the following blunt edge 16 that the skin cannot be damaged by the cutting edge 15. At the same time, the blunt edge 16 scrapes any remaining fat from the skin. The skin then passes into the region between the hollowed portion 17 and the shaft, and is constantly pressed against the shaft by the bearing pressure exerted on the blade. Consequently, the helical spring 11 takes up the position shown in Figure 1, in which it is pressed completely into the groove 10, owing to the radial bearing pressure of the skin, and therefore enables the projections to engage the skin and to remain in engagement therewith. The skin then passes into the region of the longitudinal frame 4, the side of which nearer the shaft 1 is in the form of a segment of a hollow cylinder concentric with the axis of the shaft so as to serve as a guide for the skin. The skin then leaves the machine below the frame 4 and moves into the region substantially opposite the blade 14, the helical spring 11 projecting beyond the projections 9 in this region. Thus, in the travel of the skin from the region of the blades into the opposite region, the projections 9 gradually and successively recede behind the convolutions

of the helical spring, whereby the spring presses the skin away from the projections. At the same time, in the region lying to the right of the shaft as viewed in Figure 1, the projections 9 are prevented from protruding during the operation due to the position of the spring 11, so that the fingers of the operator are well protected.

The driving projections 9 need not be in the form of knife edges as illustrated in the drawings, but they may be pointed or completely blunt, that is to say, without any edge or point.

The pins 13 and socket 12, may be replaced by any other suitable parallel guiding means between the blade and the frame. It may be expedient in some cases to form, in one part, a dovetail-shaped groove in which a correspondingly shaped guide bar on the other part can engage.

The cutting edge 15 of the blade, extending along the feed shaft, need not be parallel to the axis of the feed shaft 1 as shown in the drawings, but can in some cases, as seen in horizontal section, project furthest at the centre and be inclined on either side thereof in relation to the axis of the feed shaft. This inclined position, apart from the light inclined cut favourable to the cutting operation, also produces an appreciable automatic tensioning of the meat during treatment, as those parts of the meat which lie laterally of the central portion are pulled slightly away from one another from the centre, so that the meat is tightly stretched.

What we claim is:

1. A meat-skinning machine comprising a frame; a feed shaft rotatably mounted in the frame, the surface of said feed shaft having projections adapted to carry along the skin and also being formed with helical grooves; a blade movably mounted in said frame and having a cutting edge extending along said shaft; a helical spring arranged in said groove, said spring having such radial clearance in said groove that, when completely pressed in said groove by pressure of the skin in the region of said blade, said projections extend beyond said spring to engage the skin while, in the region remote from said blade, said spring projects beyond the projections sufficient extent to detach the skin from said projections.

2. A meat-skinning machine according to claim 1, in which said projections consist of longitudinal ribs which project from the surface of the said shaft and subdivided by said groove.

3. A meat-skinning machine according to claim 1, in which said blade is provided on the side nearer the shaft with a blunt edge parallel to and behind said cutting edge, said blunt edge being adapted to prevent said cutting edge from cutting into the skin, and to exert a scraping action.

4. A meat-skinning machine comprising a frame; a feed shaft rotatably and drivably mounted in said frame, the surface of said feed shaft being provided with projections for carrying along the skin and having a helical groove formed therein; a blade mounted in said frame and having a cutting edge extending along said shaft; means for adjusting the distance of said blade with respect to said shaft; a helical spring arranged in said groove, said helical spring having such radial clearance with respect to the said groove that, when it is completely pressed in said groove in the region of the blade under the radial bearing pressure of the skin said projections project beyond it to engage the skin, and, conversely, it projects beyond the projections in the region remote from said blade to an

extent sufficient to detach the skin from said projections.

5. A meat-skinning machine according to claim 4, comprising a pedal rotatably mounted on the frame for operation to adjust the position of said blade.

6. A meat-skinning machine according to claim 4, comprising an adjusting means provided with a return spring tending to urge said blade into its position furthest from said feed shaft.

7. A meat-skinning machine comprising a frame; two bearings connected by a web-like part of the said frame, a rotatable feed shaft mounted in said bearings and disposed parallel to said web-like part, the surface of said feed shaft being provided with projections adapted to carry along the skin and being formed with a helical groove; a blade having a cutting edge extending along said feed shaft; guides in said frame in which guides said blade is movable with respect to said feed shaft; a spiral spring arranged in said groove, said spiral spring having such radial clearance with respect to said groove that, when fully pressed into said groove in the region of the blade under the radial bearing pressure of the skin, said projections project beyond it to enable them to engage the skin while it projects beyond said projections in the region remote from the blade to an extent sufficient to detach the skin from the said projections.

8. A meat-skinning machine according to claim 7, in which said guides are mounted in said web-like part of the frame.

9. A meat-skinning machine comprising a frame; two bearings mounted in a web-like part of said frame; a feed shaft mounted in said

bearings parallel to said web-like portion, the periphery of said shaft being formed with projections adapted to advance the meat and with a helical groove; guide sockets mounted in said web-like part at right-angles to the axis of said shaft; a pin slidable in each of said guide sockets; a blade mounted on said pins and having a cutting edge extending along said feed shaft; a helical spring arranged in said groove, said helical spring having such radial clearance with respect to the said groove that, when it is pressed fully into said groove in the region of the blade under radial bearing pressure of the skin, said projections project beyond it to enable them to engage the skin, while it projects beyond the driving projections in the region remote from the blade to an extent sufficient to detach the skin from said projections.

10. A meat-skinning machine according to claim 9, in which at least one of said pins is constructed as a toothed rack and a toothed pinion meshes therewith and is arranged to extend into the corresponding guide socket, a rocking lever of an operating linkage engaging with said pinion.

WALTHER STETTLER.
